UNITED STATES PATENT OFFICE

104,889

DESIGN FOR A COMBINED GAS DISPENSER AND CANOPY

Irvin L. Tucker, Cedar Rapids, Iowa

Application March 22, 1937, Serial No. 68,342

Term of patent 3½ years

To all whom it may concern:

Be it known that I, Irvin L. Tucker, a citizen of the United States, residing at Cedar Rapids, in the county of Linn and State of Iowa, have invented a new, original, and ornamental Design for a Combined Gas Dispenser and Canopy, of which the following is a specification, reference being had to the accompanying drawing, forming part thereof.

Figure 1 is a front view in perspective of a combined gas dispenser and canopy showing my new design.

Figure 2 is a rear view in perspective of a combined gas dispenser and canopy shown in Figure 1.

The essential feature of the invention resides in the canopy.

I claim:

The ornamental design for a combined gas dispenser and canopy as shown and described.

IRVIN L. TUCKER.
